UNITED STATES PATENT OFFICE.

WYBRANTS G. OLPHERTS, OF LONDON, ENGLAND.

CHAIR-SLEEPER FOR RAILWAYS.

SPECIFICATION forming part of Letters Patent No. 433,875, dated August 5, 1890.

Application filed May 7, 1890. Serial No. 350,920. (No model.) Patented in England July 2, 1889, No. 10,702, and January 8, 1890, No. 354.

To all whom it may concern:

Be it known that I, WYBRANTS GEORGE OLPHERTS, a citizen of England, residing at 38 Ebury Street, Pimlico, in the county of London, England, have invented a certain new and useful Improvement in Chair-Sleepers for Railways, (for which I have obtained patents in England, dated July 2, 1889, No. 10,702, and dated January 8, 1890, No. 354,) 55
10 of which the following is a specification.

My invention relates to the construction of chair-sleepers for railways, such that with comparatively little weight of metal I obtain great strength and firmness of fixing in the ballast, convenient and ready means for securing the cross-ties with accuracy of gage, and a fixing of the rail without the use of wooden keys, which are liable to loosening and decay. 60
15

20 My invention is applicable either to double-headed or to flanged rails, as I shall describe, referring to the accompanying drawings.

Figure 1 is a side view, Fig. 2 is a plan, Fig. 3 is an end view, Fig. 4 is a section on the line Z Z of Fig. 2, and Fig. 5 is a plan looking from below, of a chair-sleeper, according to my invention, suitable for double-headed rails. Fig. 6 is a side view of the tie-bar. Fig. 1^a is a side view, Fig. 2^a is a plan, and Fig. 3^a is an end view, of the chair-sleeper somewhat modified to hold a flanged rail; and Figs. 4^a and 5^a are respectively a back view and a side view of the movable jaw. 65
25

30 Referring, first, to Figs. 1 to 6, inclusive, the base A of the sleeper is of rectangular form with rounded ends, having a downwardly-projecting lip B all around its edge and a central rib C projecting down into the ballast, supported on each side by two cross-ribs D. 70
35

40 One of the jaws E, which hold the rail, is cast in one piece with the sleeper. The other jaw F is fitted to slide between two side ribs G, which project up from the sleeper, and is secured in position by a wedge-key H, preferably of steel, which is driven through slots of the ribs G and through a groove of the jaw F. 75
45

50 At the one side of the central rib C slots are formed through the cross-ribs D, and the tie-bar K is made with notches k in its under edge in such positions that when the tie-bar is slid through the slots of D it can be lowered the depth of its notches k, and thus

held securely in position. In order to prevent it from rising so as to disengage its notches k, a tongue f, projecting down from the jaw F, is passed through a slot in the upper face of the sleeper and extends down to bear on the upper edge of the tie-bar K. Thus when the jaw F is keyed in position it 80
55 at the same time secures the tie-bar K. Both edges of the tie-bar K may have notches k, as shown in Fig. 6, the one set of notches suiting the gage for straight parts of the line, the other suiting the gage for curves, so that 85
60 by inverting the tie-bar it can be used under either condition. The jaws E and F are made with faces somewhat inclined to give the rail its desired tilt. They also support it under the head, so that the lower face of the rail is not deformed by hammering on the sleeper below, and consequently the rail can be inverted when required. 90
65

In Figs. 1^a, 2^a, and 3^a the parts corresponding with those in Figs. 1, 2, and 3 are marked with similar letters of reference, the only difference in the two chair-sleepers being that the jaws E and F are so shaped as to clip the flange of the rail instead of clamping its body. 95
70

Having thus described the nature of my invention and the best means I know of carrying the same into practical effect, I claim—

A chair-sleeper for railways, consisting of a bearing-plate longitudinally and transversely ribbed and lipped at the edge, having integral with it one fixed jaw and two upwardly-projecting ribs, in combination with a movable jaw secured between the said ribs by a wedge-key, and a tie-bar having notches engaged on the transverse ribs, substantially as described. 85
80

In testimony whereof I have signed my name to this specification, in the presence of two subscribing witnesses, this 24th day of April, A. D. 1890. 90
85
